UNITED STATES PATENT OFFICE

SOL H. GOLDBERG, OF CHICAGO, ILLINOIS, ASSIGNOR TO CHAIN STORE PRODUCTS CORPORATION, OF CHICAGO, ILLINOIS, A CORPORATION OF DELAWARE

DESIGN FOR A DISPLAY CARD OR SIMILAR ARTICLE

Application filed December 2, 1931. Serial No. 41,936. Term of patent 3½ years.

To all whom it may concern:

Be it known that I, SOL H. GOLDBERG, a citizen of the United States, residing in the city of Chicago, county of Cook and State of Illinois, have invented a new, original, and ornamental Design for a Display Card or Similar Article, of which the following is a specification, reference being had to the accompanying drawing, forming part hereof, in which the single figure represents a front elevational view of the article showing my new design formed on a substantially flat card.

I claim:

The ornamental design for a display card or similar article, as shown and described.

SOL H. GOLDBERG.
